US00D801975S

(12) **United States Design Patent** (10) Patent No.: **US D801,975 S**
(45) Date of Patent: **** Nov. 7, 2017**

(54) **FLASH DRIVE AND CARD READER**

(71) Applicant: **Qiang Qin**, Guangdong (CN)

(72) Inventor: **Qiang Qin**, Guangdong (CN)

(**) Term: **15 Years**

(21) Appl. No.: **29/594,312**

(22) Filed: **Feb. 17, 2017**

(30) **Foreign Application Priority Data**

Aug. 19, 2016 (CN) 2016 3 0402931

(51) **LOC (10) Cl.** **14-03**

(52) **U.S. Cl.**

USPC **D14/435.1**

(58) **Field of Classification Search**

USPC D14/435.1, 480.1–480.7

CPC H05K 5/0278; G06K 19/07732

See application file for complete search history.
